United States Patent Office

Des. 178,031
Patented June 12, 1956

178,031

MERCHANDISE DISPLAY STAND OR SIMILAR ARTICLE

Fritz Westernacher, New York, N. Y.

Application November 3, 1954, Serial No. 32,955

Term of patent 14 years

(Cl. D80—9)

Fig. 1.

Fig. 2.

I claim:

The ornamental design for a merchandise display stand or similar article, substantially as shown.
